UNITED STATES PATENT OFFICE

169,354

BUILDING

Benjamin F. Britt, St. Petersburg, Fla.

Application November 7, 1952, Serial No. 22,186

Term of patent 14 years

(Cl. D13—1)

To all whom it may concern:

Be it known that I, Benjamin F. Britt, a citizen of the United States, residing at St. Petersburg, county of Pinellas, and State of Florida, have invented a new, original, and ornamental Design for a Building, of which the following is a specification; reference being had to the accompanying drawings, forming a part hereof.

Figure 1 is a perspective view of a building, showing my new design;

Figure 2 is a bottom plan view;

Figure 3 is a side elevational view;

Figure 4 is a front elevational view; and

Figure 5 is a rear elevational view.

I claim:

The ornamental design for a building, as shown.

BENJAMIN F. BRITT.
